UNITED STATES PATENT OFFICE.

JOHN H. HUNT, OF DAYTON, OHIO, ASSIGNOR TO THE DAYTON ENGINEERING LABORATORIES COMPANY, OF DAYTON, OHIO, A CORPORATION OF OHIO.

ELECTRICAL CONTROLLING SYSTEM.

Application filed May 21, 1921. Serial No. 471,479.

To all whom it may concern:

Be it known that I, JOHN H. HUNT, a citizen of the United States of America, residing at Dayton, county of Montgomery, State of Ohio, have invented certain new and useful Improvements in Electrical Controlling Systems, of which the following is a full, clear, and exact description.

This invention relates to a system of electrical control by means of which one mechanical member may be caused to operate in synchronism with another moving member, and the invention is particularly useful in connection with synchronizing a machine gun with an airplane engine so that the gun may fire between the blades of the revolving propeller without danger of striking the propeller.

It is an object of the invention to control electrically the operation of the machine gun by means of current derived from a magneto or other generator driven by the engine and to provide for the control of the passage of current from the generator in synchronism with the engine and to synchronize with the operation of the engine the passage of current from the generator to the electrical machine gun control.

It is a further object to provide speed responsive means for modifying the operation of the synchronism apparatus in accordance with the speed of the engine so that, as regards its time relation to the engine, the gun may discharge sooner when the propeller is revolving very rapidly than when revolving at slower speeds. In this manner it will be made certain that the bullet is past the plane of rotation of the propeller before one of the blades of the propeller can come into line with the muzzle of the gun.

Other and further objects of the present invention will be apparent from the following description, reference being had to the accompanying drawings, wherein a preferred embodiment of the present invention is clearly shown.

In the drawings:

Fig. 1 shows diagrammatically a side view of an engine and machine gun to which a synchronizer embodying the present invention is applied; and

Fig. 2 is a wiring diagram showing diagrammatically the essential elements of the synchronizing apparatus.

In the drawings, the engine 20 drives a propeller 21 and a magneto 22. 23 designates the machine gun having its muzzle 24 arranged to discharge through the plane of the propeller. 25 designates the trigger motor or apparatus for controlling the discharge of the gun. This trigger motor 25 includes an electromagnet 26 having a core 27 and a winding 28 and an armature 29 pivotally mounted at 30 and normally maintained by spring 31 in unattracted position with relation to the armature core 27. The mechanism for releasing the firing pin of the gun 23 is not shown but it will be understood that this mechanism cooperates with the armature 29 in such a manner that when the armature 29 is attracted by the magnet 26, the firing pin of the machine gun 23 will be released to explode the cartridge. As the mechanism for releasing the firing pin is not a part of the present invention no description of this mechanism in detail is thought to be necessary.

The magneto 22 includes a bipolar permanent magnet 32 and an armature 33 including a two pole core 34 and a winding 35. The core 34 is secured on an armature shaft 36. Shaft 36 supports a slip ring 37, and weight disc 38 and is provided with a reduced end portion 39 upon which is mounted for relative rotation therewith a sleeve 40. The weight disc 38 carries weights 41 pivoted at 42 and having notches 43 which receive arms 44 projecting outwardly from the sleeve 40, which carries at its outer end a cam 45. The weight disc 38, weights 41, arms 44 and sleeve 40 constitute a driving connection between the cam 45 and the shaft 36. This connection provides relative rotation between the cam 45 and shaft 36 when the weights 41 move outwardly from shaft 36 through centrifugal force. Springs 46 connecting weights 41 with weight disc 38 tend to cause the return of the weights to the position shown in Fig. 2 when the speed of shaft 36 diminishes.

Cam 45 is provided with two lobes 48 and 49 which are symmetrically arranged. These lobes cooperate alternately with breaker arms 50 and 51 carrying movable contacts 52 and 53, respectively. Contacts 52 and 53 cooperate with stationary contacts 54 and 55 respectively. Springs 56 serve normally to maintain these pairs of

contacts in engagement. The armature winding 35 is grounded in some suitable manner upon the magneto frame, the magneto 22 being mounted upon and electrically connected with the engine 20. This ground connection is designated by numeral 60. The other end of armature winding 35 is connected by wire 61 with slip ring 37. The brush 62 which cooperates with slip ring 37 is connected by wire 63 with the breaker arm 50. The stationary contact 54 is grounded at 64. The wire 65 connects the breaker arm 50 with the stationary contact 55. Breaker arm 51 is connected by wire 66 with the magnet winding 28 which is grounded at 69. The condenser 70 is connected in parallel with the contacts 53 and 55, and the condenser 71 is connected in parallel with contacts 52 and 54 by reason of its ground connection 72. All of this breaker mechanism described may be suitably housed within a timer housing 73, and since the machine gun 23 is electrically connected with the engine and magneto by virtue of its mechanical connection therewith, only one wire, the wire 66, is necessary to connect the timer apparatus with the trigger motor 25.

Arrow 80 designates the direction of rotation of the propeller. The diagrammatic view of the magneto and timer shown in Fig. 2 is taken in the direction of the arrow 81 of Fig. 1, hence the arrow 83 designates the direction of rotation of the magneto armature shaft 36.

The magneto 22 is so timed with relation to the engine that the peak of the current wave will occur several degrees of crank shaft rotation after one of the blades of propeller 21 has moved out of alignment with the gun muzzle 24. When the peak of the current wave in the armature coil 35 is reached, the armature core 34 will be approximately in the position shown in Fig. 2. At this time the cam 45 will engage the breaker arm 50 to separate the contacts 52 and 54. The separation of these contacts interrupts the short circuit of the magneto armature winding 35, hence the energy of this winding will be suddenly discharged through the electromagnet winding 28 to effect the attraction of armature 29 and release of the firing pin of the gun 23. The armature winding 35 is connected with the electromagnet winding 28 through the following circuit: winding 35, wire 61, slip ring 37, brush 62, wire 63, wire 65, contacts 55, 53, breaker arm 51, wire 66, magnet winding 28, ground 69, ground 60 to magneto armature winding 35.

In order to limit the time during which the electromagnet winding 28 is energized, the cam 45 will operate upon the breaker arm 51 after the contacts 52 and 54 have been separated. When contacts 53 and 55

have been separated by means of the operation of cam 45 upon breaker 51, current will cease to flow from the magneto armature winding 35 to the magnet winding 28. Therefore it is not necessary to wait until the current in magneto armature winding 35 diminishes to zero before the electro-magnet winding 28 will be deenergized. Therefore the armature 29 controlling the release of the firing pin can return to firing pin retaining position before the breaker arm 50 is again operated on by one of the lobes of the cam.

By providing the speed responsive mechanism for advancing the cam 45 with respect to the shaft 36, the range of operation of the machine gun measured in degrees of propeller rotation, can be limited to a relatively small value. Therefore as regards the liability of a bullet striking one of the propeller blades, a greater degree of safety can be maintained.

While the form of mechanism herein shown and described constitutes a preferred form of embodiment of the invention, it is to be understood that other forms might be adopted, all coming within the scope of the claims which follow.

What I claim is as follows:

1. In a system of electrical control, the combination with a magneto having an armature winding, of an electromagnet and an armature operated thereby; means operating in synchronism with said armature to effect discharges of current from said magneto armature winding through said magnet in recurrent sequence; and means for determining the duration of said discharges whereby said electromagnet will be deenergized at a predetermined time.

2. In a system of electrical control, the combination with a magneto having an armature winding; of an electromagnet and an armature operated thereby; means operating in synchronism with said armature to effect discharges of current from said magneto armature winding through said magnet in recurrent sequence; and a circuit breaker operating in synchronism with said magneto armature for disconnecting said electromagnet from said magneto armature after said discharges have continued for a predetermined period.

3. In a system of electrical control, the combination with a magneto having an armature winding; of an electromagnet and an armature operated thereby; means for connecting said electromagnet with said magneto armature including a circuit breaker; a second circuit breaker for normally short-circuiting said magneto armature winding; and means operating in synchronism with said magneto for operating said breakers in recurrent sequence, said first breaker opening after the second breaker has opened.

to determine the period of discharge from said magneto armature to said electromagnet.

4. In a system of electrical control, the combination with a bipolar magneto having a two-pole armature including a winding; of an electromagnet and an armature operated thereby; means for connecting said magneto armature with said electromagnet including a circuit breaker; means normally short-circuiting said magneto armature winding including a circuit breaker; and a symmetrical two lobe cam operating in synchronism with said magneto armature intermittently to open said breakers in recurrent sequence, the relation of the breakers to the cam being such that the first mentioned breaker is opened a predetermined time after the second breaker is opened.
5. In a system of electrical control, the combination with a magneto having an armature winding, of an electromagnet and an armature operated thereby; means operating in synchronism with said armature to effect discharges of current from said magneto armature winding through said magnet in recurrent sequence; means for determining the duration of said discharges whereby said electromagnet will be deener-

gized at a predetermined time; and means so for advancing the time of operation of said magnet controlling means with increase in speed of rotation of the magneto.

6. In a system of electrical control, the combination with a magneto having an armature winding, of an electromagnet and an armature operated thereby; means for connecting said electromagnet with said magneto armature including a circuit breaker, a second circuit breaker for normally short-circuiting said magneto armature winding; means operating in synchronism with said magneto for operating said breakers in recurrent sequence, said first breaker opening after the second breaker has opened to determine the period of discharge from said magneto armature to said electromagnet; and means for advancing the time of operation of said magnet controlling means with increase in speed of rotation of the magneto.

In testimony whereof I hereto affix my signature.

JOHN H. HUNT.
